The ornamental design for a spinal fusion implant, as shown and described.

DESCRIPTION

3,486,505 A	12/1969	Morrison
3,518,993 A	7/1970	Blake
3,604,487 A	9/1971	Gilbert
3,745,995 A	7/1973	Kraus
3,848,601 A	11/1974	Ma et al.
4,026,304 A	5/1977	Levy
4,026,305 A	5/1977	Brownlee et al.
4,646,738 A	3/1987	Trott
4,657,550 A	4/1987	Daher
4,743,256 A	5/1988	Brantigan
4,781,591 A	11/1988	Allen

FIG. 1 is a perspective view of an intervertebral implant showing our new design;

FIG. 2 is another perspective view thereof;

FIG. 3 is still another perspective view thereof;

FIG. 4 is a top view thereof;

FIG. 5 is a side view thereof;

FIG. 6 is a first end view thereof; and,

FIG. 7 is a second end view thereof.
